UNITED STATES PATENT OFFICE.

JOHN T. WILSON, OF JERSEY SHORE, PENNSYLVANIA.

PACKING FOR PISTON-VALVES.

1,042,683.

Specification of Letters Patent.

Patented Sept. 9, 1913.

Application filed November 15, 1912. Serial No. 731,537.

To all whom it may concern:

Be it known that I, JOHN T. WILSON, a citizen of the United States, residing at Jersey Shore, in the county of Lycoming and State of Pennsylvania, have invented certain new and useful Improvements in Packings for Piston-Valves, of which the following is a specification.

The object of the invention is the provision of a packing so constructed that should an edge of a ring forming part of said packing be excessively expanded or projected into a port far enough to catch or engage the edge of the metal bounding the port the entire packing cannot be broken or disarranged sufficiently to render the valve inoperative and prevent the locomotive from drawing the train to its destination or to a place where another locomotive may be substituted.

To the attainment of this end the invention consists in fashioning the packing rings with grooves and inner beveled edges, the groove in a packing ring extending entirely around the same and located a suitable distance from its outer edge, three-sixteenths of an inch more or less, said groove preferably being bounded by a vertical surface and a surface disposed to the said vertical surface at an angle of 45 degrees, and the inner beveled edge of a ring being located adjacent to the edge of a bull ring, or in a semi-plug valve adjacent to the edge of a wide or central ring, which latter may also have its edges beveled, the angle of the beveled edges being 45 degrees more or less. By reason of this particular or similar construction of the rings, should the edge of a ring from any cause whatsoever be excessively expanded or forced outwardly far enough into a port to catch the metal bounding the edge of the same, a short portion of the edge of the packing ring will be broken or torn off and the beveled surface bounding the groove adjacent to the line of breakage will force the ring back to its normal position within the cage and the entire packing not be broken and rendered inoperative. Furthermore, should the beveled inner edge of a ring be expanded or projected beyond its normal position, the beveled surface at the edge engaging the metal bounding the port will force the ring back to its proper position without breaking the ring or disarranging the packing as a whole.

The accompanying drawing illustrates the

physical embodiment of the invention in connection with three species or types of packing rings, the same being constructed according to the best modes of procedure I have so far devised for the purpose, but the invention may be embodied in connection with other types of valve packings when so desired.

Figure 1 is a section of part of a semi-plug piston valve showing the grooves in the two packing rings, the inner beveled edges of the same, and the beveled edges of a wide or intermediate ring. Fig. 2 is a section of another type of packing having a bull ring 70 and L-shaped or flanged packing rings, each with a groove and an inner beveled edge. Fig. 3 is a plan view of part of the exterior surface of the packing illustrated by Fig. 2. Fig. 4 is a section of a piston valve having 75 packing rings which are substantially rectangular in cross section.

Referring to all the figures, the letter A designates part of the spool of the piston valve; B, the follower; C, the recess between the flanges of a spool and follower within which the packing is confined; D, the expansible packing rings, each having a lap joint of any suitable construction; E, the circumferential grooves in the packing rings, 85 each groove preferably being bounded by a vertical surface 1 and a beveled surface 2 disposed to the said vertical surface at an angle of about 45 degrees, and F designates the inner beveled edges of the packing rings, 90 the surface of the bevel in each example being at an angle of about 45 degrees to a vertical plane taken at right angles to the length of the valve.

In Fig. 1 integral wall rings G, an expansible wedge ring H, and an expansible wide ring I are shown in section, the same constituting parts of a semi-plug valve. The wide ring I has its edges J beveled where said edges meet the edges of the snap 100 rings, the surfaces of the bevels being approximately at angles of 45 degrees to the length of the valve.

In Figs. 2 and 4 bull rings K of a well known construction are shown which carry 105 the snap or packing rings.

In Figs. 1 and 2 the vertical and oblique surfaces defining the grooves are joined by horizontal surfaces L, and in Fig. 4 the surfaces meet. However, the size or dimensions 110 of the grooves and the angular dispositions of the surfaces defining the same may be

varied in the embodiment of the invention. The construction and arrangement should be such that a part of the edge of a packing ring may be broken off and the beveled surface bounding the groove force the ring back to its normal position within the cage without deranging the packing sufficiently to render the valve entirely inoperative, and modifications of shape and dimensions may be adopted to attain the desired end without constituting substantial departures.

From the description and illustrations of the embodiments of the invention it will be clear that packing rings provided with safety grooves and beveled edges will prevent the breaking or derangement of piston valve packings sufficiently to render them permanently inoperative.

What I claim is:

- 20 1. A piston valve having a packing ring provided with a circumferential groove in its exterior surface and near one of its edges, one surface defining the groove being a beveled surface.
- 25 2. A piston valve having a packing ring provided with a circumferential groove defined by a vertical surface and a surface at an angle to the first mentioned surface.
- 30 3. A piston valve packing comprising two expansible rings and an intermediate ring, each of said expansible rings having a rectangular outer edge to present a sharp steam line and a circumferential groove in the exterior surface thereof located adjacent to its said rectangular outer edge.
- 35 4. A piston valve packing comprising

two expansible rings and an intermediate ring, each of said expansible rings having a circumferential groove in the exterior surface thereof located adjacent to its outer edge and one of the surfaces defining the groove being a beveled surface.

5. A piston valve having two expansible rings, the exterior inner edge of each being beveled, for the purpose set forth.

6. A piston valve having two expansible rings and an intermediate ring, the exterior edges of the expansible rings adjacent to the intermediate ring having beveled surfaces.

7. A piston valve having an expansible ring with a circumferential groove in the body thereof and one of the exterior edges of said ring beveled.

8. A piston valve having two expansible rings, each with an inner beveled edge F, and an intermediate ring with beveled edges J adjacent to the said beveled edges of the expansible rings.

9. A piston valve having two expansible rings, each with a circumferential groove therein adjacent to its outer edge and a beveled exterior inner edge, and an intermediate ring with beveled edges adjacent to the said beveled edges of the expansible rings.

In testimony whereof I affix my signature in presence of two witnesses.

JOHN T. WILSON.
